DIRIGIBLE LIGHT

Clifford Sklarek, Chicago, Ill., assignor to International Spotlight Corporation, Chicago, Ill., a Corporation of Illinois

Application October 11, 1930. Serial No. 487,975

7 Claims. (Cl. 240—61.13)

This invention relates to improvements in dirigible lights, and more particularly dirigible lights adapted for use on automobiles and other automotive vehicles, which lights are commonly called spotlights. The present invention is in the nature of an improvement on such type of light shown in my co-pending application 253,820 filed February 13, 1928, now Patent 1,906,489, issued May 2, 1933.

10 The type of dirigible light referred to comprises, in its broadest aspects, an outer head housing on which is rotatably mounted about one axis a lamp casing; a handle housing at the opposite or inner end, the head and handle housings being rigidly united to rotate in unison about a different axis, by a hollow tubular connection; an operating handle rotatably mounted on the handle housing; an electric control switch on the handle housing; an operating mechanism between the handle and the lamp casing extending through the hollow tubular connection for imparting rotation to the lamp casing about its axis of rotation, the two housings and tubular connection also enclosing the electrical conductors. More specifically, dirigible lights of the type above referred to and particularly as shown in my said co-pending application 253,820, have means for automatically eliminating lost motion or backlash between the movable parts and to compensate for wear to thereby prevent looseness or rattling when the light is in service.

An object of the present invention is to provide a dirigible light of the type hereinbefore referred to and possessing all of the desirable characteristics thereof, the present improvement being such as to reduce the number of necessary parts to a minimum without any loss of advantages or functions to the end that the cost of material and labor of assembly may be greatly reduced.

Another object of the present invention is to provide in a dirigible light of the type indicated, an efficient electric switch comprised of few parts with low cost of manufacture and such that the switch may be readily applied to the handle housing or removed for repairs or inspection without disturbing or disassembling any of the other parts.

50 Still another object of the invention is to provide a supporting and attaching bracket for the light, which bracket is specially formed to adapt it as a drill guide in boring the usual hole through the automobile superstructure or the like for receiving the tubular connection, to

thereby minimize the cost of application of the light.

Other objects of the invention will more clearly appear from the description and claims hereinafter following.

In the drawings forming a part of this specification, Figure 1 is a part vertical, sectional view, part elevational view of a dirigible light embodying my improvements, showing the same applied to the body of an automobile. Figure 2 is an enlarged, detailed, sectional view illustrating more particularly the construction of the improved electric switch in the handle housing of the light. Figures 3 and 4 are sectional views corresponding to the section lines 3—3 and 4—4 respectively of Figure 2. And Figure 5 is a somewhat enlarged, detailed, sectional view corresponding to the line 5—5 of Figure 1.

In said drawings, 10 denotes a corner post or other part of the super-structure of an automobile or other automotive vehicle to which my improved light is adapted to be attached, although as will be understood by those skilled in the art the light is applicable to outside installations by suitable modification of the attaching brackets. The improved light, as shown, comprises a head housing A; a handle housing B; a tubular connector C rigidly assembled with both of the housings A and B; a lamp casing or shell D; an operating handle E; together with suitable attaching brackets, switch and other parts hereinafter described.

The head housing A is preferably in the form of a casting having two main sections 11 and 12 disposed approximately at right angles to each other, the housing A being hollowed out, as clear from Figure 1. The section 11, disposed vertically as shown in Figure 1, has an interior circular recess 13 and an inwardly extending flange or web 14, the latter having a journal bearing 15. On its upper face, as shown in Figure 5, said section 11 is formed with a circular recess 16 into which extends, radially, a stop or limiting lug 17 for the purpose hereinafter described. In axial alignment with the recess 13 at the bottom of the section 11 is an opening 18 of the same or slightly larger diameter than the recess 13, said opening 18 being closed by a removable, light sheet metal, snap cover or cap 19. In the section 12 of the housing A horizontally disposed, as shown in Figure 1, is a circular recess 20 having a shoulder 21 at its inner end, said section 12 being rigidly secured to the corresponding or outer end of the tubular connection C, as shown in Figure 1. In horizontal axial alignment with the recess 20, the 110

housing A is provided, at its outer end, with an opening 22 of the same or slightly larger diameter than the recess 20, said opening 22 being adapted to be closed or covered by a similar, light sheet metal snap cap or closure 23.

Rotatably journaled in the bearing 15, is the shank 24 of a bevel gear 25, the gear 25 being of larger diameter than the shank 24 and providing a shoulder 26 between which and the opposed shoulder formed by the flange or web 14, is interposed an expansion spring 27 normally urging the gear 24-25 downwardly, as viewed in Figure 1. Said gear 24-25 with the spring 27 assembled on the shank thereof, is adapted to be inserted in place upwardly through the opening 18. Bearing against the upper end of the gear shank 24 is the lower flat face of a saddle or block 28, the upper face of which is conformed to fit the lamp casing D. Said block or saddle 28 has a hollow upstanding hub 29 preferably of non-circular cross section extended through a correspondingly shaped opening in the shell D. On the interior of the shell D is a specially shaped spring washer 30 having a horizontal section 31 against which seats the head 32 of an axially perforated bolt 33 that is extended loosely down through the saddle block 28 and threaded within the shank 24 of the gear 24-25. By screwing the bolt 32-33 tightly into the gear 24-25, it is evident that the casing D will be tightly clamped between the washer 30 and block 28 and the latter in turn tightly clamped to the gear 24-25.

On its underside, the block 28 is bored to tightly receive therein a pin 34, the lower end of which works within the recess 16 in the upper face of the section 11 of the head housing A, it being obvious that said pin 34 will be limited in its rotation by engaging the radial lug 17, best shown in Figure 5, so that the lamp casing will be limited to rotation slightly less than 360°. As shown in Figures 1 and 5 the pin 34 is so located that it is partially received within a shallow groove 35 in the hub of the gear 24-25 so that said pin also functions as a key or spine between said gear and the saddle block 28, to insure their rotation in unison and in both directions without danger of the bolt 32-33 becoming loose or unscrewed.

With the construction so far described, it will be observed that not only will the lamp casing always be rotated in unison with the bevel gear 24-25 but that, because of the spring 27, the saddle block will always be maintained taut against the upper bearing face of the section 11 of the housing A, thus eliminating any looseness and automatically compensating for any wear which may occur on the two relatively rotating surfaces.

Where the light is mounted for so-called "inside" control, as shown in Figure 1, a supporting attaching bracket of the type indicated at 36 will be employed, the same having laterally extended flanges 37-37 by which it may be attached by screws to the post or other support 10. The bracket 36 has a relatively elongated, horizontally disposed, cylindrical section 38 within which is preferably cast a thin sleeve 39 of steel or other suitable hard material and of an accurate inside diameter to function as a guide for a drill in boring the hole 40 through which the tubular connection C is ultimately passed. In applying lights of the type disclosed, particularly to the corner posts of automobiles, extreme accuracy is required in drilling the hole for the tubular connection, since the corner posts are now of relatively small cross section and care must be taken to clear the

windshield glass, etc. in drilling the hole, it being true as to certain makes of automobiles that there is not more than a possible leeway of $\frac{1}{16}$ or $\frac{1}{8}$ of an inch in centering the hole to be drilled. Heretofore, it has been customary to first spot the drill hole by employing a temporarily applied drill guide. With my improved bracket 36, this procedure is done away with, the bracket 36 being accurately located and the drill must necessarily accurately follow its intended path. Preferably, the bracket 36 at its outer end has a relatively thin flange 41 overhanging a reduced section 42 on the inner end of the housing A so as to provide an additional bearing support for the housing A in its rotation about a horizontal axis.

On the inside of the post or other support 10, is a second inside bracket 43 having diametrically disposed arms also adapted to be secured by screws. Said bracket has a split hub bearing section 44, the friction between which and the tubular connection C may be adjusted by means of the screw bolt 45. To limit the rotation of the tubular connection C about the horizontal axis and also to prevent the same from working outwardly, a split collar 46 is frictionally secured thereto, as by means of an adjusting screw bolt 47, said collar 46 having a shoulder 48 cooperable with a shoulder 49 on the bracket 43 to limit the rotation, as will be understood.

The handle housing B is preferably in the form of a casting having a main horizontal section 50 split and secured to the tubular connection C, as by the adjusting screw bolt 51. Depending from the horizontal section 50 is a hollow bearing section or extension 52, the latter having an interior annular recess 53 providing a shoulder 54 near the bottom thereof. The tubular connection C is extended within the housing B and contains within it a hollow shaft 55, the latter carrying a bevel gear 156 at its outer or left hand end, as viewed in Figure 1, which gear meshes with the gear 25. The righthand end of the shaft 55 is extended inwardly of the tubular connection C and made of square or other non-circular cross section so as to receive thereon a bevel gear 56, the latter rotating with the shaft but being slideable or adjustable lengthwise thereon. Said gear 56 has a journal section 57 rotatable in a corresponding journal bearing in the housing B.

Rotatably mounted in the depending section 52 of the handle housing is a driving bevel gear 58 meshing with the gear 56. Said gear 58 has a preferably integral depending shank 59 terminating in a pyramidal lower section 60 and over the extended end of which is fitted the handle proper E, the latter being non-rotatably but detachably secured thereto, as by a counter sunk screw 61 threaded into the lower end of the gear shank 59. To compensate for inaccuracies of manufacture and to take up wear, one or more shims 62 may be interposed between the upper end of the handle proper E and the lower end of the depending section 52 of the handle housing. To maintain the parts taut and to prevent backlash, a coil spring 63 is slipped over the shank 59 and interposed between the gear 58 and the shoulder 54, it being evident that said spring will normally urge the gear 58 upwardly into tight mesh with the gear 56. To permit assembling of the gear 58 and its shank in the housing B, the latter is provided at the top thereof with an opening 64 of diameter equal to or slightly larger than that of the gear 58, said opening being normally closed by a sheet

metal snap cover or cap 65, the latter preferably being of the same size as the cap 23 so as to permit use of the same size caps and reduce cost of manufacture.

5 The righthand end of the housing B, as viewed in Figure 1, is open and is provided with diametrically disposed slots 66 and 67 of different width (see Figure 3) to receive endwise therein, two corresponding radially extending lugs 68 and 69 of a lead-in block 70 made of bakelite or other suitable insulating material. By reason of the different size slots and lugs 66, 67, 68 and 69, improper assembly of the lead-in block within the housing is thereby prevented. Said lead-in block 10 is of generally circular form and centrally thereof has moulded therein a preferably brass combined binding post, bearing and contact element 71, the inner end of which is enlarged, as indicated at 72, and centrally apertured to receive the stripped end 73 of an electrical wire or conductor 74, the same being held by a binding screw 75. The other or righthand end of the element 71 is of reduced diameter, as indicated at 75', and forms a journal bearing for an insulated 20 rotor or knob 76. To one side of its center, the lead-in block 70 has also moulded therein a metal contact 77 to which is soldered the stripped end 78 of the lead-in wire 79 which, as shown in Figure 1, is entered through the inner end of the housing B and fixed to the tubular connection C by a suitable ring clip 80. As will be understood, said conductor 79 leads to a suitable source of 30 electricity, as for instance, the battery of the car. The rotor 76 is moulded with a specially shaped recess, best shown in Figures 2 and 4. Said recess comprises two spaced circular portions 81—81 connected by a transverse recess 82 to thereby receive a specially formed spring, which 35 comprises two coils 83—83 with a connecting section 84 therebetween. The free end of one of the coils 83 is so positioned as to be brought into and out of contact with the contact element 77 of the lead-in block 70. The free end of the other coil 83 bears upon the section 75' of the contact member 71 so that when the rotor 76 is 40 in the position shown in Figure 2, the current passes from the lead-in wire 79—78 through the spring 83 to fixed contact element 71 and thence from the latter through the conductor 73—74, which in turn is passed through the shaft 55 and thence through the bolt 32—33 into a socket shell 86 in the lamp casing where its other stripped end is secured to a contact 87 mounted 50 in a spring influenced insulated washer 88. Said contact 87 is adapted to engage the usual contact at the inner end of a lamp bulb 89.

The rotor 76 has an inner annular enlargement 90, thereby forming a shoulder so that said 60 rotor is held in assembled position by means of a sheet metal cap or ferrule 91, the latter in turn being secured to the housing B by two screws 92—92, which also have their inner ends entered in recesses 93—93 in the lead-in block so as to 65 also retain the latter in proper position within the housing B. To limit the rotative movement of the rotor 76, the latter is provided with an arcuate recess 94 within which is extended a lug 95 formed integral with the lead-in block 70, the angular throw being limited, as will be evident from an inspection of Figure 4. With the construction shown and referring particularly to Figure 2, it 70 will be evident that the spring 83—84 normally urges the rotor 76 outwardly or toward the right 75 and will thereby create sufficient friction between

said rotor and the cap 91 to hold the rotor in any angular adjusted position.

Referring now to Figure 1, the socket shell 86 has its inner end of reduced section, as shown at 96, the same being interiorly threaded to receive a screw 97, the latter having its head counter sunk in the casing D. Said screw 97 carries a washer 98 between which and the casing is a spring 99, thereby normally urging the socket shell 86 toward the left but permitting adjustment axially thereof by the screw 97 so as to properly focus the lamp bulb with respect to the reflector 100.

In assembling the parts, the following general procedure is followed. Assuming the head housing A and tubular connection C secured together, the bevel gear 156 with its shaft 55 secured thereto and the spring 20 slipped thereover, is entered endwise through the opening 22 of the housing A. Next, the gear 24—25 with the spring 27 assembled thereover is entered vertically through the opening 13, the gear 156 being pressed to the right during this operation sufficient to permit clearance in entering the gear 25. After the latter is in place, the gear 156 is released and will be forced into mesh by the spring 20. The saddle block 28, casing D, washer 30 and bolt 32 are then brought together and secured by the bolt, as will be understood. The conductor 74 is then put in place and suitably connected to the contact 87 within the casing D, these parts constituting the head end assembly ready for shipment. The handle housing B has the gear 58, spring 63 and handle E assembled therewith, as hereinbefore described. The switch assembly is also applied and secured to the handle housing B in the manner indicated in the preceding description. When the light is applied to a car, the bracket 36 is secured in place, the hole drilled and then the tubular connection C, with the lamp head assembly attached thereto, has its extended end passed through the bracket 36 to the inner side of the support 10. The inner bracket 43 is then applied and the limiting ring 46. The handle housing B is then slipped over the end of the tubular connection C and secured tightly in place by the screw bolt 51. During this operation, the gear 56 is slipped over the squared end of the shaft 55, it being understood that said gear 56 has been slid into place before the switch assembly is applied, the gear 58 being depressed for this purpose while the gear 56 is inserted in its bearing in the handle housing B. With the handle housing now applied to the tubular connection C, the cap 65 is removed and the stripped terminal 74 secured 130 to the binding post by the screw 75, whereupon the light is ready for operation, as soon as the lead-in wire 79 is connected to a suitable source of current.

With the construction described, it is evident 135 that access to the various parts is at all times available and that the several sub-assemblies may be removed or replaced without the necessity of taking down the entire light. Further, because of the several springs employed and located as described, all lost motion and backlash is eliminated and compensation provided for wear so as to eliminate rattling or looseness when in service. The number of parts required is greatly reduced, as compared to any other light of generally similar type and the cost of manufacture and assembling correspondingly reduced.

Although I have herein shown and described what I now consider the preferred manner of carrying out my invention, the same is merely 150

illustrative and I contemplate all changes and modifications that come within the scope of the claims appended hereto.

I claim:

5. In a dirigible light, the combination with longitudinally separated head and handle housings rigidly united by a tubular connection and together rotatable as a unit about the axis of the tubular connection, said head housing having an 80 integrally formed bearing therein and a shoulder adjacent said bearing; of a gear journaled in said bearing, said gear having a shoulder; a lamp casing; means rigidly connecting said casing and gear to rotate in unison; a handle carried by the handle housing; operating means between said 85 handle and gear for effecting rotation of the latter and casing; and yielding means directly interposed between said shoulders of the head housing and gear, the head housing having an opening opposite said shoulder of the head housing and 90 through which said gear may be entered and removed.
20. In a dirigible light of the character described, the combination with a housing; of two meshing gears rotatably journaled within said 95 housing, said gears having their axes at an angle and intersecting at a point within the housing; an expansion spring interposed between one of said gears and the housing normally urging said gear toward the other, said housing having two openings provided therein, one opening being axially opposite one of the gears and the other axially opposite the second of the gears and adapted to 100 permit passage of the respective gears therethrough for assembling with the housing said spring allowing of temporary retraction of its corresponding gear during assembling.
30. In a dirigible light of the character described, the combination with a head housing having two 105 journal bearings therein, the axes of which are disposed substantially at right angles to each other; a pair of meshing bevel gears journaled in the respective bearings; and expansion springs interposed between each gear and the housing, said 110 springs normally urging the gears into mesh with each other and said housing having two openings axially opposite the two gears respectively, permitting insertion of the gears therethrough for assembling with the housing, the 115 springs adapting the gears for temporary retraction when being assembled.
40. In a dirigible light of the character described, the combination with a head housing; of a driven 120 gear journaled in said housing; a lamp casing; a saddle block on the outer side of said casing bearing on one end of said gear; a pin carried by said 125 block having an extended end movable in a groove of the housing; means limiting the angular movement of said pin with respect to the housing; a washer within the casing; and a bolt extended through said washer, block and gear, rigidly 130 uniting the same for rotation in unison with respect to the housing.
50. In a dirigible light, the combination with longitudinally separated head and handle housings rigidly united by a tubular connection; a lamp casing rotatably mounted on the head housing; a lateral extension on said handle housing having a journal bearing therein; a driving gear journaled in said bearing, said gear having a shank extended through said extension; a handle secured to the extended end of said shank; yielding means interposed between said gear and extension normally urging said gear endwise, said handle housing having an opening axially opposite said gear to permit insertion of the latter therethrough; and operating means between said gear and casing for effecting rotation of the latter. 135
60. In a dirigible light of the character described, the combination with longitudinally separated head and handle housings rigidly connected by a hollow tubular connector; of a lamp casing rotatably mounted on one of said housings; an operating handle rotatably mounted on the other of said housings; driving mechanism between said handle and lamp casing for effecting rotation of the latter upon rotation of the handle, said mechanism including a pair of meshing gears disposed in one of the housings and an operating shaft extending through the connector, said meshing gears being beveled and the axes thereof intersecting within the housing, said housing having openings disposed axially opposite each of said gears whereby said gears are adapted to be entered and removed endwise through the respective openings; and yieldable spring means interposed between the back side of one of said bevel gears and an adjacent portion of the housing, whereby said bevel gear may be temporarily moved to retracted position when the other cooperable bevel gear is inserted or removed. 140
70. In a dirigible light of the character described, the combination of longitudinally separated head and handle housings rigidly united by a tubular connector; of a lamp casing rotatably mounted on the head housing; an operating handle rotatably mounted on the handle housing; driving mechanism between said handle and lamp casing for effecting rotation of the latter upon rotation of the handle, said mechanism including a driving gear located in the handle housing and connected to the handle, said handle housing having an opening opposite said driving gear whereby the latter may be inserted or removed; a switch unit detachably mounted on the handle housing opposite the end of said connector, said switch unit having a binding post disposed within the handle housing and opposite said opening thereof; and an electrical conductor extending from said binding post through the connector to the lamp casing, connection and disconnection of said conductor with the binding post being effected through said opening of the handle housing. 145

CLIFFORD SKLAREK.
